UNITED STATES PATENT OFFICE.

ALGERNON S. BANGS, OF AUGUSTA, MAINE.

WINDOW-FRAME POCKET.

SPECIFICATION forming part of Letters Patent No. 257,637, dated May 9, 1882.

Application filed January 13, 1882. (No model.)

To all whom it may concern:

Be it known that I, ALGERNON S. BANGS, of Augusta, in the county of Kennebec and State of Maine, have invented a new and useful Improvement in Window-Frame Pockets, 5 of which the following is a specification.

My invention relates to an improvement in means of closing window-pockets through which the sash-weights are passed in the frames of windows. As usually constructed, the piece that closes the pocket-opening is beveled off at each end, and the ends thus beveled are secured at the back or inside of the frame at one end by a screw or nail, and at the opposite or 15 outside end in a similar manner, which latter fastening is taken out when the pocket cover is removed. The objection to this method of securing is that the inside end is not accessible after the window-frame is secured in place. 20 In the event of the giving way of the inside fastening it is very difficult to remedy the defect, rendering it necessary to remove the casing. Again, the fastening at one end is never sufficiently strong to properly secure the pocket-cover, thus rendering it liable to give way under undue pressure.

It is the object of my invention to obviate these objections; and to this end my invention consists in constructing the piece that closes 30 the opening of the pocket with a bevel at one end and a groove in the other end, which groove fits upon a corresponding dowel secured to the frame of the window, so that by inserting the said piece into the opening of the pocket it will be firmly secured at one end by the dowel and 35 at the other end by means of a screw or pin.

Referring to the drawings, Figure 1 is a front view of a portion of a window-frame, showing the position of the pocket. Fig. 2 is a side 40 view of the same, and Fig. 3 is a view of the piece that covers the pocket-opening.

B represents the portion of the window-frame containing the pocket through which the sash-weight is passed to be attached to the cord.

A is the pocket cover or piece which closes 45 the opening. It is made with a bevel, E, at one end. In the opposite end is formed a groove, D, extending lengthwise across the same, as shown in Fig. 3. In one end of the opening of the window-frame is fixed a dowel, 50 D', as shown in Fig. 2. This dowel may be placed either at the upper or the lower end of the opening, and the piece A correspondingly fitted in the same; but I generally prefer placing it in the upper end, as shown in the drawings. 55

The grooved end D of the piece A may be beveled at its upper end in the direction of its width, as shown in Fig. 1, for the purpose of retaining it more firmly in position in the frame.

In fitting the piece A in place the upper or 60 grooved end, D, is placed upon the dowel D', which may be of metal or wood, and the lower beveled end, E, is fitted in the corresponding beveled portion of the frame, where it is secured by a screw or pin, F, as shown. 65

By the use of a dowel, as shown, I effect a crossing of the grain of the wood, which serves to strengthen it and obviates completely the liability to split out, as would be the case with a square tenon and mortise; and, again, the use of a dowel admits of the same piece being employed for the cover that is taken from the frame, which cannot be done where a tenon and mortise are used. 70

What I claim as my invention is— 75

The combination, in a window-frame pocket, of the cover A, having grooved end D and the dowel D', secured to the window-frame, as set forth.

In testimony whereof I have signed my name 80 to this specification in the presence of two subscribing witnesses.

ALGERNON S. BANGS.
